UNITED STATES PATENT OFFICE.

MICHAEL T. DEVINE, OF PIERRE, SOUTH DAKOTA.

DRIFT-PIN PULLER.

1,130,071.

Specification of Letters Patent.

Patented Mar. 2, 1915.

Application filed June 19, 1912. Serial No. 704,632.

To all whom it may concern:

Be it known that I, MICHAEL T. DEVINE, a citizen of the United States, and a resident of Pierre, in the county of Hughes and 5 State of South Dakota, have invented a new and Improved Drift-Pin Puller, of which the following is a full, clear, and exact description.

This invention relates to implements for 10 pulling spikes, nails, pins, or the like, and has particular reference to an implement of this nature which is better adapted than those usually employed for use in connection with bolts or pins which are to be pulled 15 rapidly and with great force and which, furthermore, are to be preserved in straight condition.

The invention consists in the construction 20 and combination of parts to be more fully described hereinafter and particularly set forth in the claim.

Reference is to be had to the accompanying drawings forming a part of this specification in which like characters of reference 25 indicate corresponding parts in all the views, and in which—

Figure 1 is a side elevation of the preferred embodiment of the invention as applied for use, a portion of the jack being 30 broken away; Fig. 2 is a front elevation of the device, parts of the toes being in section; Fig. 3 is a transverse sectional detail of a modification; and Fig. 4 is a transverse section on the line 4—4 of Fig. 1.

Referring particularly to the drawings for a description of the construction, I show at 10 a jack shank 11 of any suitable size, form or strength, and arranged substantially at right angles thereto is a foot 12. 40 The outer end of the foot is formed into a pair of toes 13 of any suitable length and between said toes is provided a space 13^a, said space being bounded in the rear by an undercut and curved wall 12^a. As indicated 45 in Figs. 1 and 2 the opposing inner walls of the toes 13 are provided with open-topped sockets 14 in transverse alinement with each other.

The numeral 16 indicates an eccentric 50 having gudgeons 17 adapted to drop into the sockets 14 and constituting a pivotal bearing or support for the eccentric. The eccentric 16 may be of any suitable form or size and is adapted to extend sufficiently far 55 toward the wall 12^a of the shank to cause the pin or device to be operated upon by the im-

plement to be clamped snugly within the aforesaid space 13^a by virtue of the eccentricity of the eccentric. The particular form of sockets 14 shown in Figs. 1 and 2 60 makes it expedient for eccentrics of different size or eccentricity to be used in connection with a single shank and to readily exchange one for another if the devices being operated upon vary in size or construction, making 65 such change desirable. Another object of the ready removability of the eccentric is to provide for the application of the implement to a spike or bolt which may have a head which would otherwise render it im- 70 possible for the tool or implement to be applied thereto. In other words, by lifting out the eccentric, the toes 13 may be caused to span the bolt, even though said bolt may have a head, and the eccentric may then be 75 dropped into place, automatically operating to clamp the bolt as before described.

In Fig. 3 is shown a similar shank 11 and toes 13' between which is formed a space 13^a as before. The eccentric 16', however, is 80 shown journaled loosely upon a pivot bolt 14' extending transversely through said toes 13'. The operation of this form of the invention is similar to that above described.

Considering the device illustrated at 18 as 85 a drift pin used in connection with bridge construction or elsewhere where metallic plates are being assembled, said pin will be driven as usual, but it is either undesirable to drive the pin out because of the damage 90 to its point which would result, or for the reason that the smaller or inner end of the pin is many times inaccessible for this purpose; therefore, in applying the device, as herein set forth, to the pin, and lifting the 95 shank 11, the pin 18 will be drawn properly and yet will not be damaged by bending or the like. After the pin is withdrawn a slight tap on its point will release the grip of the eccentric thereon.

The herein described implement may be 100 constructed of any suitable material and the parts thereof may be proportioned as best suited for any particular purpose. It is to be noted that the eccentric may be knurled on its gripping surface if found desirable, but this is not essential in all cases.

Having thus described my invention, what I claim as new and desire to secure by Letters Patent is:—

A drift pin puller comprising a handle 110 forming bar having one of its ends bent at

a right angle to provide a foot including two claws held in parallel spaced relation, with flat outer base forming faces and rounded ends, the wall formed at the union of said claws being curved and extending at an acute angle to the axis of said bar so that the upper end of said wall forms a biting lip, two open-topped sockets arranged in transverse alinement within said claws, and 10 a disk having eccentrically disposed gudgeons for co-action with said sockets, the ends of said claws being rounded.

In testimony whereof I have signed my name to this specification in the presence of two subscribing witnesses.

MICHAEL T. DEVINE.
